UNITED STATES PATENT OFFICE.

ERNEST C. DERSEWEH AND JOSEPH M. DICKENS, OF RIDGETOP, TENNESSEE.

RAIL-JOINT.

1,125,978.

Specification of Letters Patent. Patented Jan. 26, 1915.

Application filed February 4, 1914. Serial No. 816,629.

To all whom it may concern:

Be it known that we, ERNEST C. DERSEWEH and JOSEPH M. DICKENS, citizens of the United States, residing at Ridgetop, in the county of Robertson and State of Tennessee, have invented certain new and useful Improvements in Rail-Joints, of which the following is a specification, reference being had to the accompanying drawings.

10 This invention relates to new and useful improvements in rail splices and more particularly to a device which is rigidly spiked to the ties and is adapted to be arranged at the meeting ends of two rails to securely 15 hold the rails in their operative positions upon the ties.

The device is also removably applied to the rail ends so that the same may be quickly and readily placed in position or removed 20 from the rail ends.

Another object of the invention is the provision of a rail splice of the above character which possesses advantages in points of efficiency and durability, is inexpensive to 25 manufacture and at the same time is simple in construction and operation.

With the above and other objects in view, the invention consists in the novel features of construction and the combination and arrangement of parts to be hereinafter more 30 fully described, claimed and pointed out in the accompanying drawings, in which—

Figure 1 is a perspective view of a rail chair constructed in accordance with our 35 invention; Fig. 2 is a transverse sectional view; Fig. 3 is a detail perspective view of a portion of the base plate.

In carrying out our invention, we provide a base plate 1 which is formed of metal and 40 provided at its longitudinal edges with inwardly projecting recesses 2 adapted for the reception of the securing spikes 3. Projecting upwardly from the base 1 and extending longitudinally along one edge thereof 45 is a flange 4, the inner face of which is arcuately curved, as shown at 5 to provide a suitable socket, the purpose of which will be more fully described hereinafter. Suitable end members are arranged at each end 50 of the flange 4 so as to close the ends of the socket. Arranged upon the longitudinal edge of the base 1 opposite the flange 4 are the upwardly projecting lugs 7, the upper inner faces of which are preferably perpendicular, as illustrated at 8, thence curved, 55 as shown at 9, and secured to the base di-

rectly in front of each of the lugs upon the inner side thereof are the sleeves 10.

The splice bars 13 and 14 which are arranged upon opposite sides of the rail ends 60 11 and 12 are preferably formed of metal and substantially angular in form, as clearly illustrated in Fig. 2. The outer longitudinal edge of the horizontal portion of the splice bar 14 is provided with a longitudinal 65 knuckle 15 adapted to be movably disposed within the socket 5 of the flange 4. Formed integral with the knuckle and projecting inwardly in spaced relation with the horizontal portion of the plate 14 is a bearing 70 flange 16 which is adapted to bear against the base plate 1 and retain the angular plates in their operative positions and also retain them against further inward movement after they have been arranged in their 75 effective positions.

The angular plate 13 is provided at its outer longitudinal edge with the sleeves 17 which are arranged in pairs at each end of the plate and adapted to be disposed upon 80 opposite sides of the sleeve 10 which is secured to the base 1. Removable pins 18 are arranged within said sleeves to securely hinge the plate 13 to the base member 1. It will be noted that when the sleeves 17 85 are in position they are arranged adjacent the curved portion 9 and the perpendicular portion 8, thus allowing the angular plate 13 to swing outwardly or inwardly, as desired. Formed integral with the outer longitudinal edge of the plate and projecting 90 inwardly in spaced relation with the horizontal portion is a second bearing plate 16' which is adapted to bear against the upper face of the base 1 to limit the inward swing- 95 ing movement of the plate 13 and assist in retaining the plate in its effective position.

The rail ends 11 and 12 are provided in their upper portions with openings 19 and formed on the inner face of the vertical portion of the plate 13, are the inwardly projecting lugs 21 which are adapted to be disposed within the openings 19 when the plate 13 is in its effective position to retain the rail ends 11 and 12 against longitudinal 100 movement when arranged in position between the spliced ends. The base plate 1 is provided at one side thereof with an opening 22, whereby a bar or other tool may be inserted through the opening to force the 105 base or the splice bars in position if desired. In placing the rail ends in position 11

within our improved device, the plates 13 and 14 are first arranged within their opposite positions, then moved outwardly so that the bases of the rail ends may be dropped between the plates and also drop downwardly until they strike the upper edges of the inwardly projecting members 13 and 13'. The said plates 13 and 14 are then pressed inwardly, the outer longitudinal rail edges of the bases of the rail fitting between the members 16 and 16' and the horizontal portions of the plates 13 and 14. It will be noted that as the said plates 13 and 14 are pushed inwardly into position, the rail ends will drop downwardly into their proper position and further downward pressure upon the rails will readily place them in their proper position. In order to remove the rail ends the pins 18 are first withdrawn, the rails are then tilted so as to displace the plates 13 and 14 after which both the rail ends may be readily removed. It will be noted that when the rail ends are locked in position, as above described, it will be impossible to remove them without first removing the pins 18. These pins may be provided upon their inner ends with a transverse securing pin 19, so that they may be securely held in place after the rails have been positioned between the splice plates. From the above, it will be readily apparent that we have provided a simple and durable device whereby the meeting ends of two rails may be quickly and effectively connected together and securely held against any longitudinal or lateral movement whatever. The rail ends may be quickly placed in position or re-

moved and the device itself is extremely simple in construction and can be placed upon the market at a comparatively small cost.

While we have shown and described the preferred form of our invention, it will be obvious that various changes in the details of construction and in the proportions may be resorted to for successfully carrying our invention into practice without sacrificing any of the novel features or departing from the scope of the appended claim.

We claim—

A rail joint comprising a base provided along one side with a continuous rib, the inner face of which is formed with a longitudinal ogee seat, and along its other side with a plurality of hinge butts, having their inner faces also formed with ogee seats, a pair of splice plates, one of which is provided with a longitudinal knuckle to engage the ogee seat of the rib, and the other with spaced butts to interlock with those on the base, means for pivotally connecting the two sets of butts, and means carried by one of the splice plates to project through the webs of a pair of rails seated on the base.

In testimony whereof we hereunto affix our signatures in the presence of two witnesses.

ERNEST C. DERSEWEH.
JOSEPH M. ^{bis} DICKENS.
